190,174

ACOUSTIC TILE OR SIMILAR ARTICLE

Philip M. Brody, Scarsdale, and Frederic H. Rahr, New York, N.Y., assignors to Wood Conversion Company, St. Paul, Minn., a corporation of Delaware

Filed Mar. 25, 1960, Ser. No. 59,868

Term of patent 14 years

(Cl. D18—2)

Fig. 1 is a front face view of a tile showing our new design and,

Fig. 2 is an enlarged fragmentary view taken substantially on the line 2-2 of Fig. 1.

The stippled areas in Fig. 1 have been shaded to indicate contrast.

We claim:

The ornamental design for an acoustic tile or similar article, substantially as shown and described.
